UNITED STATES PATENT OFFICE.

RALPH C. DUNHAM, OF NEW BRITAIN, CONNECTICUT.

IMPROVED BUCKLE AND RING.

Specification forming part of Letters Patent No. **58,619**, dated October 9, 1866.

To all whom it may concern:

Be it known that I, RALPH C. DUNHAM, of New Britain, in the county of Hartford and State of Connecticut, have invented a new and Improved Buckle and Ring; and I do hereby declare that the following is a full, clear, and exact description thereof, which will enable those skilled in the art to make and use the same, reference being had to the accompanying drawings, forming part of this specification, in which—

Figure 1 represents a front view of this invention. Fig. 2 is a transverse section of the same.

Similar letters of reference indicate corresponding parts.

This invention consists of a buckle or ring composed of a metal core covered with or protected by vulcanized india-rubber or other vulcanizable gum in such a manner that a strong, cheap, and durable buckle or ring is obtained, which is not liable to wear out the leather straps, and which lasts much longer than an ordinary leather-covered buckle or ring.

A represents a buckle or ring, which is composed of a metal core, *a*, and a covering, *b*, of hard vulcanized india-rubber or other vulcanizable gum. Said covering is produced in suitable molds, and the gum is colored to imitate leather.

By these means a buckle or ring is obtained which is not liable to wear out the leather straps passing through the same, and the covering *b*, of hard rubber or other gum, is much more durable than the ordinary leather covering, and, furthermore, it is much easier applied.

What I claim as new, and desire to secure by Letters Patent, is—

A buckle or ring composed of a metal core, *a*, and a covering, *b*, of india-rubber or other vulcanizable gum, substantially as and for the purpose described.

RALPH C. DUNHAM.
